UNITED STATES PATENT OFFICE.

WILLIAM G. BERGMAN, OF TOLEDO, OHIO.

BURNER.

1,411,470.

Specification of Letters Patent. Patented Apr. 4, 1922.

Application filed August 7, 1920. Serial No. 401,961.

To all whom it may concern:

Be it known that I, WILLIAM G. BERGMAN, a citizen of the United States, and a resident of Toledo, in the county of Lucas 5 and State of Ohio, have made an Invention Appertaining to Burners; and I do hereby declare the following to be a full, clear, and exact description of the invention, such as will enable others skilled in the art to which 10 it appertains to make and use the same, reference being had to the accompanying drawings, and to the characters of reference marked thereon, which form a part of this specification.

15 My invention has for its object to provide a burner for furnaces which is provided with efficient means for causing a thorough mixture of the air with the gases to be consumed. It also particularly has for its object to provide in connection with such a 20 burner, a means whereby the portion of the burner having air and gas outlets may be readily disconnected from the gas main.

The invention may be contained in burners of different forms to be used for different purposes. To illustrate a practical 25 application of the invention I have selected one of the structures containing the invention and shall describe it hereinafter. The 30 structure selected is illustrated in the accompanying drawings.

Figure 1 of the drawings is a sectional view of the burner. Fig. 2 is a front view of the burner. Fig. 3 is a rear view of the 35 burner.

1 in the figures, is an upwardly extending drum which is connected with the gas main. The upper edge of the drum is provided with a channel 2 and a shell 3 is so located 40 that its lower edge is positioned in the channel 2. The channel 2 may be filled with a sealing material, such as, sand, in order to prevent the escape of the gas from the interior of the shell 3. The shell 3 is 45 provided with a large opening 4 located on one side of the shell. A large inner nozzle 5 surrounds the opening 4 and is contained within the nozzle 6 so as to leave an annular space 7 between the nozzles 5 and 6. 50 The annular space near the edges of the nozzles is tapered so as to form a narrow slit 8 that surrounds the nozzle 5. The edge 9 on one side of the narrow opening 8 is located a short distance behind the edge 20 of the nozzle 5 located on the other side of 55 the narrow opening 8 to produce a flaring

effect of the air that enters the annular space 7 under pressure. The shell 3 is also provided with a large pipe 10 which is smaller than the opening 4 and terminates 60 a short distance behind the opening 4 and within the shell 3. The pipe 10 is also connected with a source of air pressure supply and the air passing through the pipe 10 operates as an ejector to cooperate to 65 move the gas to and through the burner. The nozzle 5 is provided with a plurality of openings 11 that extend diagonally through the outer portion of a nozzle 5 and radiate cone-wise rearwardly from the axis of the 70 nozzle 5.

The air moving through the pipe 10 under pressure mixes and cooperates to move the gas through the shell 3 and the opening 4. The pipe 10 being located behind the open- 75 ing 4, operates as an ejector to thus move the gas with a considerable speed through the shell 3 and the opening 4. During this movement of air and gas together, the air pressure within the chamber 7 causes a flow 80 of diagonal currents of air from the openings 11 and through the stream of gas from the shell 3. This produces a thorough mixture of the air and gas. Moreover, the air passing through the narrow slit or opening 85 8 causes a spreading of the flow of air and gas over a large area and at the same time surrounds the gas with a current of air which produces combustion as the currents progress in the furnace and thus extends the 90 area of the heating zone of the flame.

The burner is so formed that it may be easily disconnected from the gas supply line, it being merely set into the channel 2. The drum 1 moreover, is provided with a slide 95 valve 12 so that when the shell 3 is removed, the valve 12 may be closed and thus the escape of gas prevented. The slide valve member 12 which is in the form of a plate is connected to a rack 13 which is operated 100 by means of a lever 14 having a dog 15 that engages with the teeth of the rack 13 to open or close the valve. The pipe 10 may also be provided with a slide valve 16. Also the pipe 17 which is connected with a source 105 of air pressure supply and with the nozzle 6 may be closed by means of the valve 18. The shell may also be provided with an opening 19 for the purpose of burning or cleaning out the interior of the shell 3. If desired, 110 a plurality of such openings may be formed in the shell 3. The opening 19 may be

closed by a ball 20 placed in the channel or groove 21 formed in a boss 22 located on the shell 3.

I claim:—

- 5 1. In a gas burner, a shell having a chamber into which the gas is directed and having a comparatively large opening located on one side of the chamber, a pipe connected with a source of air pressure supply and terminating within the chamber, the axis of the pipe passing through the center of the opening and the end of the pipe located a short distance from the opening, a nozzle located outside the chamber and 10 surrounding the opening, a second nozzle 15 surrounding the first named nozzle and forming an annular chamber, a source of air pressure supply connected to the chamber between the nozzles, the edges of the said nozzles located in substantially the same plane and forming a narrow annular 20 outlet between the edges of the nozzles for delivering concentric streams of fluid material from the burner from substantially the 25 same plane.
2. In a gas burner, a shell having a chamber into which the gas is directed and having a comparatively large opening located on one side of the chamber, a pipe connected 30 with a source of air pressure supply and terminating within the chamber, the axis of the pipe passing through the center of the opening and the end of the pipe located a short distance from the opening, a nozzle

surrounding the opening, a second nozzle 35 surrounding the first named nozzle and forming an annular chamber, and a source of air pressure supply connected to the chamber between the nozzles, the edges of the said nozzles located in close proximity 40 to each other to form a narrow annular outlet, the edge of the outer nozzle being located slightly behind the edge of the inner nozzle and the inner nozzle being flared 45 outward.

3. In a gas burner, a shell having a chamber into which the gas is directed and having a comparatively large opening located on one side of the chamber, a pipe connected with a source of air pressure supply 50 and terminating within the chamber, the axis of the pipe passing through the center of the opening and the end of the pipe located a short distance from the opening, a nozzle surrounding the opening, a second nozzle 55 surrounding the first named nozzle and forming an annular chamber, and a source of air pressure supply connected to the chamber between the nozzles, the edges of the said nozzles located in close proximity 60 to each other to form a narrow annular outlet, a drum having a slide valve for closing the said drum and a channel for supporting the shell, and means located in the channel for sealing the shell.

In testimony whereof I have hereunto signed my name to this specification.

WILLIAM G. BERGMAN.
